LASTING APPARATUS.

1,271,659.

Specification of Letters Patent.

Patented July 9, 1918.

Application filed December 18, 1914. Serial No. 877,985.

To all whom it may concern:

Be it known that I, MATTHIAS BROCK, a citizen of the United States, residing at Boston, in the county of Suffolk and State 5 of Massachusetts, have invented certain Improvements in Lasting Apparatus, of which the following description, in connection with the accompanying drawings, is a specification, like reference characters on the drawings indicating like parts in the several 10 figures.

This invention relates to shoe machines, particularly to machines for lasting shoes, and has special applicability to the lasting 15 of the toes thereof. An embodiment of the invention is shown by way of exemplification as combined with the toe lasting head of a lasting machine of the type fully described in Letters Patent of the United 20 States No. 1,018,477, granted on my application, February 27, 1912. In the use of machines of this type for lasting the toes of shoes, it is usual to employ a hand tool known as a retarder to hold the margin of 25 the upper stock frictionally upon the toe embracing wipers and allow it to slip or render under tension over the edge of the wipers as they are raised to stretch the upper up the side faces of the toe of the 30 last, and as they wipe the upper over the edge of the shoe bottom on to the feather of the innersole. A tool commonly used comprises a handle and a plate secured at 35 right angles to the handle, and having an edge that may be pressed against the upper. Sometimes, also, a lever is employed to carry the retarder and to assist in forcing it against the upper. In the use of such a tool, however, it is possible and in fact 40 frequently happens, that the upper is held too tightly with the result that it is either torn or the tip seam is bent or bowed toward the toe of the shoe by the excessive 45 strain.

It is an object of this invention to provide a mechanism which will render it practically impossible for the operator, however inattentive or unskilled he may be, to apply an excessive tension on the upper, 50 while, at the same time, he will be enabled to get upon the upper all the tension that is desirable from the standpoint of good lasting.

One important feature of the invention

consists in a device which is constructed 55 and arranged to engage the upper and press it against the wipers, combined with means by which the tension that can be applied to the upper is limited to an amount which the upper will safely bear. In the construction shown the retarder comprises stock engaging members which are movably mounted upon a carrier shaped to conform somewhat to the contour of the shoe, the members having only a frictional engage- 60 ment with the carrier. As the retarder is pressed against the upper, therefore, the stock will be held against the wiper until the strain upon the stock overcomes the friction between the movable members and 65 the carrier.

In accordance with another feature of the invention the stock engaging members are movable independently of one another and when the tension adjacent to a given movable member becomes excessive this member will move and relieve the tension at that point so that the strain upon different portions of the upper is equalized and distributed with no danger of an excessive tension being applied to any particular portion. In the construction shown, the movable members present to the work a type of rolling bearing, said members having the form of cylindrical bead-like bodies which 75 are strung or threaded upon a carrier which is in the form of a resilient loop and is of a shape to bring the bead-like members into engagement with the upper around the 80 curved contour of the toe.

Preferably the adjacent ends of the beads or cylinders interengage or are otherwise articulated with each other, as, for example, by a concave end on one bead fitting over a convex end on an adjacent one. As a result the engaging face of the retarder is substantially a continuous line extending around the toe and may, if desired, be co-extensive with the wipers.

During the vertical movement of the 100 wipers relatively to the last, above referred to, the upper is being stretched from the body portion toward the edge, but after the wipers begin to close and bend the upper over the feather of the innersole no substantial further stretching can take place, and the additional stock required to cover the feather must come from above and render 105

down across the edge of the wipers. If the retarder continues to resist this movement of the upper with the same force as when the upper was being stretched up there is danger of injuring the stock, and the upper is unnecessarily strained. Another feature of this invention provides means to meet this situation. As illustrated the retarder is mounted for movement toward the heel of the shoe and the upper stock is therefore allowed to render over the edge of the wipers and is laid down upon the feather of the innersole. In accordance with the preferred embodiment of this feature of the invention the material required to be wiped over the feather is automatically supplied to the wipers without excessive strain being applied thereto. For this purpose means is provided for giving the retarder a movement toward the heel of the shoe, which is connected with the wiper closing mechanism. Preferably this movement of the retarder is coincident with but in excess of the rearward movement of the wipers, and, in theory, should be substantially twice that movement of the wipers since the movement of a point upon the margin of the upper which is frictionally held by the retarder against the upper face of the wipers is twice the movement of the edges of the wipers themselves over the shoe bottom.

The wipers, of course, have a closing movement at the sides of the toe, while the retarder is substantially rigid laterally. At the sides of the toe, therefore, the movement of the wipers is in excess of the movement of the retarder so that during the closing movement of the wipers over the shoe bottom at the sides of the toe there is a substantially increased tension applied to the upper transversely of the toe, which tends to maintain the tip seam straight and results in improved lasting of the toe.

45 As a further feature of the invention the loop of the retarder which is of resilient material is so constructed that its ends can be adjusted laterally of the shoe, whereby the size and shape of the retarder may be modified and the retarder is thereby adapted for use on wide and narrow toes and on toes of various shapes and sizes.

55 In lasting shoes having pronounced right and left characteristics, it is important that the retarder member shall have a contour corresponding closely to the contour of the toe portion of the shoe bottom whether it be that of a right shoe or of a left shoe.

According to another feature of this invention, the retarder is given the contour, for example, of a right shoe and is constructed and arranged to be removed from its holder, turned over and replaced therein to adapt it for use upon a left shoe.

65 These and other features of the invention will appear more fully from the following

detailed description when read in connection with the accompanying drawings, and will be pointed out in the appended claims.

In the drawings,—

Figure 1 is a view in perspective of the head of a bed lasting machine having an embodiment of the present invention incorporated therein;

Fig. 2 is a perspective view of a modification of the construction shown in Fig. 1; 75

Fig. 3 is a detail of the construction shown in Fig. 2;

Fig. 4 is a detail partly in section of the presser members on the retarder; and

Fig. 5 is a perspective view of a hand implement embodying features of this invention. 30

In Fig. 1 is represented the head of a lasting machine of the type shown and described

in the patent referred to. This head has a 85
depending stem 1 which can be raised relatively to the frame 3 and a shoe supported on the usual toe rest for the operation of wiping up the sides of the toe of a shoe, and can be depressed for ironing down the stock 90 on the shoe bottom. The head is provided with wipers 2 which are mounted on carriers 4. The carriers are arranged to be advanced and closed to carry the wipers over the shoe bottom by means of a lever 6 fulcrumed at 8, and having connection by a link 10 with a rod 12 (broken away) which is mounted for movement longitudinally of its axis, and carries at the end next the wipers a cross 95 bar 14. Each end of the cross bar 14 is pivoted at 16 to a link connecting it with one of the wiper carriers 4. The direction of movement of the wiper carriers is determined by slots 18 and 20 in the carriers 4, which coöperate with relatively stationary 100 rolls 21 mounted in the head of the machine and engaging the said slots. The inclination of the slots 18 and 20 is such that the move- 105

ment of the bar 12, which is communicated to the wipers is divided into two components, one of which provides the advancing movement of the wipers and the other their closing movement. These movements are substantially equal and hence the advancing movement of the wipers is only about half 115

the movement of the rod 12. A slide 30 is connected at 32 to the rod 12 and is therefore moved with the wipers longitudinally of the shoe but at a rate substantially twice the corresponding movement of the wipers. 120

At the end of the slide 30 which is nearest the shoe ears 34 are provided, in which slots 36 are formed extending lengthwise of the shoe. A pin 38 mounted in the slots 36 forms the fulcrum of a lever 40 which extends longitudinally of the shoe in a position to be conveniently grasped and manipulated by the operator. A member 42 is mounted on the lever 40 and is held in longitudinal adjustment thereon by a set screw 130

44. The member 42 is provided with depending arms 46 through the lower ends of which a rod 48 passes. The ends of a loop 50 of resilient wire may, as shown in Fig. 1, be bent around the rod 48 to form a pivotal connection therewith and to form a yielding connection between the loop and its end portions which are turned outwardly to engage apertures 52 formed in plates 54 5 mounted on the rod 48 at each side of the member 42, and having at their upper ends screw and slot adjusting means 56 for the purpose of varying the normal inclination of the loop relatively to the plane of the sole bottom. Upon the loop 50 a series of bead-like presser members 60 are threaded or strung. This arrangement constitutes means to be manipulated by the lever 40 to force the upper against the wipers, and also, 20 if desired, against the forward faces of the wiper carriers, during the lasting operation. The members 60 may be substantially cylinders to form a roller bearing on the upper stock. The members 60 may have approximately spherical curved working faces 25 forming a ball bearing on the upper stock and producing separate closely adjacent lines of strain as the retarder is used. The adjacent ends of the members 60 may be rounded, as shown in Fig. 2, or the adjacent ends may be articulated by forming them respectively concave and convex so that one may fit into the other, as shown in Figs. 1 and 4. By this construction the members 30 35 60 present a substantially continuous line or surface to engage the upper.

When not in use the lever 40 may be turned forwardly over the head of the machine about the pivot 38 and, to prevent the lever from going so far as to be out of convenient reach of the operator, a stop 62 may be provided which engages the top plate of the machine, and supports the device at an inclination in which the handle is conveniently accessible.

To provide for lateral adjustment of the ends of the retarder loop to accommodate the retarder to different widths of shoes and to different sizes of toes the construction shown in Fig. 2 may be employed. Here the ends of the retarder loop are straight and are seated in holes 53 in blocks 55 which are threaded to engage right and left threaded portions of a rod 49. The rod 50 55 is provided centrally with a thumb head 57 by which it may be rotated to adjust the blocks, and hence the ends of the retarder loop equally and oppositely laterally of the shoe. To provide for adjustment of the inclination of the retarder relatively to the plane of the sole the plates 54 in this construction are extended forwardly, and a rod 61 is passed through the forward extensions and through ears 63 upon the blocks 55. To retain the ends of the retarder in the blocks

and yet provide for their ready removal to enable the retarder to be reversed for use upon the toes of either right or left shoes, spring plungers 65, Fig. 3, are provided which engage notches or depressions 67 in the ends of the retarder loop and tend to maintain the retarder in operative position but permit it to be readily withdrawn for reversal.

In the use of the machine the shoe is jacked, the hold-down 64 is applied, and the lever 40 is brought from its inoperative position to the position shown in Fig. 1. The loop 50 is normally held at a downward inclination by the engagement of the outturned end portions 52 or by the rod 61, Fig. 2, with the plates 54, and this angle may be varied to suit different conditions by means of the screw and slot adjustment 56. When the head of the machine of this type 85 is lowered to bring the plane of the wipers somewhat below the plane of the inner-sole, the end or bight of the loop 50, by reason of the downwardly inclined position of the loop, engages the upper first, and, as the lever 40 is depressed, forces the toe portion of the upper over and down upon the wipers at the point of the toe and clamps it at the toe against the forward faces of the wiper carriers. As the head of the machine is raised, therefore, with the loop 50 pressing the upper down upon the wipers, and, if desired, also clamping it against the wiper carriers, a strong tension is applied 90 to the upper longitudinally. This tensioning action, however, is limited to the amount of force necessary to cause the rolls 60 to rotate upon the loop 50, thereby rendering it practically impossible to tear or over-stretch the stock, even if the operator, by carelessness or lack of judgment, applies excessive pressure to the handle 40. The amount of tension he can get on the upper is, therefore, limited automatically by the 95 operation of the members 60 to the strain which the upper can safely bear. The position of the loop 50 longitudinally of the machine may be varied by the operator to suit different conditions of work by reason of the slot and pin connection 36, 38 and the size and shape of the loop may be varied by the lateral adjustment 57.

As soon as pressure is applied by the member 50 to the upper there is sufficient friction at the said pin and slot connection so that considerable pressure may be applied to the work before the pin will slide in the slot, and when the pin 38 reaches the rear end of the slot still greater pressure may be applied to the work by the lever 40. At the same time, as the lever 40 is depressed and the lasting head raised, the area of contact of the loop 50 spreads from the point of the toe toward the sides of the toe until practically the whole toe portion is held 100 105 110 115 120 125 130 135 140

against the wipers and against the adjacent edges of the carriers 40. The resiliency of the loop 50, together with the capacity of the members 20 to turn before excessive tension is applied to the upper at any given point, prevents the operator, however unskilled or inattentive he may be, from so straining the toe portion of the upper that the toe tip seam is bowed or the upper torn, 10 as sometimes occurs in the use of retarders of the usual type.

After the upward movement of the toe embracing wipers to effect longitudinal tensioning of the upper, the stock is usually 15 pressed by the wipers against the side faces of the end of the last to maintain the lasting tension. When the wipers have reached the plane of the last bottom and are beginning to close over the edge of the innersole, 20 however, further stock is required to cover the feather. If this stock is taken from the upper material below the wipers excessive and unnecessary strain is apt to be given to the lasted upper, and there is a great tendency 25 also to crumple the feather of the innersole. The stock for this purpose should, therefore, be taken from the material above the wipers which, by the retarder of usual construction, is held hard down upon the 30 top of the wipers. By the connection between the retarder and the wiper operating mechanism, movement of the retarder toward the heel of the shoe is effected and the upper stock is therefore allowed to render 35 over the edge of the wipers, and is laid upon the feather of the innersole. To effect this result without taking material from under the wipers the movement of the free edge of the upper and of the retarder should 40 be substantially twice that of the movement of the wipers themselves. This is the case in the described construction as the advance movement of the wipers is only about half of the movement of the rod 12, the full 45 movement of which is transmitted to the retarder. The amount of movement of the retarder may be varied and controlled by the handle 40 and, if less than twice the 50 movement of the wiper is permitted to the retarder, additional tension will be applied to the portion of the upper which is wiped into engagement with the feather. This operation is sometimes necessary to remove 55 completely the wrinkles from the upper and to produce good lasting over the feather of the innersole.

At the point of the toe, the retarder moves with the wipers as they advance, but at a 60 greater rate, thereby tending to reduce the strain on the upper at the tip of the toe which is liable, if carried to excess, to bow the tip. At the side of the toe, on the other hand, the retarder has no movement inwardly corresponding to the closing movement of the wipers and, therefore, the clos-

ing movement of the wipers at the sides of the toe is in excess of the movement of the retarder so that the strain on the stock laterally of the toe is in excess of that longitudinally of the toe during the closing movement of the wipers, whereas, during the raising of the lasting head vertically, the strain upon the upper is very largely longitudinally of the shoe. 70

In Fig. 5 is shown a hand tool which embodies many of the advantageous features of this invention. The loop 50 is similar to that shown in Fig. 1, and is mounted in a similar manner upon a rod 48 mounted in a yoke 70, provided with a handle 72. The 80 members 74 may be similar to the members 60 of Fig. 1, but are shown in Fig. 2 as being in the form of cylinders with adjacent ends chamfered or rounded so that the area of contact at their ends is reduced, at 85 least, the point of contact is brought nearer to the center so that they rotate more freely relatively to each other upon the loop 50. In operation this loop is held in position with the members 74, pressed against the 90 upper materials to hold them against the upper surface of the wipers, and the machine is manipulated in the same manner as has been described in connection with the constructions shown in Figs. 1 and 2. The resiliency of the loop 50 and the capacity of the members 74 each to rotate individually upon the loop 50, in case there is excessive strain applied to any portion of the upper, render it substantially impossible for the 95 operator to overstrain the upper when using this tool, and a better lasted toe is the result. In Fig. 5 the loop 50 is shown as wider where it is attached to its support than in 100 Fig. 1, and this adapts it to be brought down over the toe of the last when the wipers are depressed, and to hold the upper against the wipers during their upward movement, first at the point of the toe, and then, as the wipers ascend, to extend its action toward 105 the side of the toe. 110

Having fully described my invention, what I claim as new and desire to secure by Letters Patent of the United States is:—

1. Toe lasting apparatus having, in combination, toe lasting wipers, a carrier, said wipers and carrier being constructed and arranged for relative movement toward and from each other, and stock engaging means mounted upon said carrier and comprising more than two independent movable members adapted to engage the upper and press it against the wipers, said members being constructed and arranged to move with the upper in the direction of strain when the tension becomes excessive. 115

2. Toe lasting apparatus having, in combination, toe lasting wipers, a support, a loop of resilient material mounted on the support, and a series of separately mov- 120 125 130

able upper contacting members mounted upon the loop and adapted to contact with and press the upper over and down upon the wipers during the lasting operation.

5 3. Toe lasting apparatus having, in combination, toe lasting wipers constructed and arranged to be advanced and closed over the edge of the shoe bottom, a carrier constructed and arranged to be forced toward

10 the wipers, and a series of three or more members movably mounted upon the carrier for holding the upper frictionally against the wipers, each of said series being adapted to move upon the carrier when the 15 tension upon the upper adjacent to a given movable member becomes excessive, whereby the strain upon that portion of the upper is diminished and the strain upon the upper as a whole is equalized and distributed.

20 4. Toe lasting apparatus having, in combination, toe embracing wipers; and an upper holding device comprising an operating member and a bowed wire provided with an upper engaging member constructed 25 and arranged to grip the upper upon the top face of the wipers and adapted to turn to facilitate the slipping of the upper between it and the wipers.

5 5. Toe lasting apparatus having, in combination, toe embracing wipers adapted to close over the end of a toe; and an upper holding device comprising an operating member and a member constructed and arranged to overlie the upper upon the top face 35 of the wipers and provided with a plurality of upper engaging rolls mounted to turn in directions normal to the lines of strain on the upper.

40 6. Toe lasting apparatus having, in combination, toe embracing wipers; and an upper holding device comprising an operating member, a wire bowed into the shape of the edge face of the wipers, and a series of articulated rolls on the bowed wire to grip 45 the upper upon the top face of the wipers.

7. Toe lasting apparatus having, in combination, toe embracing wipers, and an upper holding device comprising an operating member and a carrier member constructed 50 and arranged to overlie the upper upon the top face of the wipers and having rolling bearings on the upper.

55 8. Toe lasting apparatus comprising a retarder in the form of a resilient loop; a support for the ends of the loop and means for adjusting the ends of the loop toward and from each other to vary the lateral extent of the loop.

60 9. Toe lasting apparatus having, in combination, toe embracing wipers; and an upper holding device pivotally supported in front of the wipers and having an operating arm extending backwardly over the shoe, and an upper engaging member supported at 65 its ends and bowed to extend about the toe,

said upper engaging member and operating arm being constructed and arranged for relative adjustment to vary their normal angular relation.

10. Toe lasting apparatus having, in combination, a toe lasting head, a lever mounted on the lasting head for movement longitudinally of the shoe, a yoke adjustably secured to said lever, the arms of the yoke being disposed downwardly, a resilient loop mounted 70 at its ends on the arms of said yoke, and a series of movable upper engaging members mounted upon said loop.

11. Toe lasting apparatus having, in combination, toe lasting wipers and means for 80 holding down the upper of a shoe toe upon the wipers to facilitate the application of lasting tension to the shoe upper at the toe during upward movement of the wipers, comprising a loop, and a series of separate 85 movable bead-like members threaded upon the loop and adapted to contact with the upper and permit the upper to slip under them when excessive tension is applied to a portion of the upper adjacent to any given 90 member.

12. Toe lasting apparatus having, in combination, toe supporting means, toe lasting wipers movable upwardly relatively to the shoe; and means for holding the upper of 95 a shoe toe upon the wipers to facilitate the application of lasting tension to the shoe upper at the toe during upward movement of the wipers, comprising a curved carrier, and a series of cylindrical members each 100 having one end concave and the other convex and which are strung upon said carrier and disposed so that the convex end of one fits into the concave end of the next whereby a substantially continuous line of contact is 105 provided between the upper material and the curved series of cylindrical members.

13. Toe lasting apparatus having, in combination, a vertically movable head, wipers carried thereby, operating means for the 110 wipers to close and advance them over the edge of the shoe bottom, a retarder adapted to hold the upper against the wipers during the vertical movement of the head, and means for moving the retarder toward the 115 heel end of the shoe as the wipers move over the shoe edge.

14. Toe lasting apparatus having, in combination, a vertically movable head, wipers and operating means therefor to close and 120 advance them over the edge of the shoe bottom, retarding means for holding the upper down upon the wipers during their upward movement, and means for moving the retarding means toward the heel of the shoe 125 at a rate in excess of the movement of the wipers over the shoe edge.

15. Toe lasting apparatus having, in combination, a vertically movable head, wipers and operating means therefor to close and 130

advance them over the edge of the shoe bottom, retarding means for holding the upper against the wipers at the end and sides of the toe, means for moving the retarder toward the heel of the shoe during the closing movement of the wipers to prevent excessive longitudinal strain upon the upper, and means for increasing the lateral strain upon the upper in the direction of the tip seam 10 during the closing movement of the wipers.

16. A toe lasting apparatus having, in combination, toe lasting wipers, a support, a retarder comprising an open loop shaped to the contour of one toe of a pair, and connections between the loop and the support whereby the loop may be removed and replaced the other side up so as to fit the other 15 shoe of the pair.

17. A toe lasting apparatus having, in combination, toe lasting wipers, a support, a loop of resilient material constructed and arranged to coöperate with the wipers in lasting the shoe upper and having notched 20 ends adapted to engage the support, and 25 spring pins mounted in the support and adapted to engage the notched ends of the

loop to maintain the loop frictionally in operative position but permitting its ready removal.

18. A toe lasting apparatus comprising a 30 yoke, a rod mounted in the ends of the yoke, blocks mounted on the rod, a retarder having its ends seated in the blocks, and means for adjusting the blocks toward and from each other to vary the size of the retarder. 35

19. A toe lasting apparatus having, in combination, toe lasting wipers and a retarder comprising a member shaped to embrace a toe and constructed and arranged to clamp the upper upon the wipers, and supporting and operating means constructed and arranged to hold the side portion of the clamping members secured in different positions of adjustment from and toward each other for differences in sizes of shoes. 40 45

In testimony whereof I have signed my name to this specification in the presence of two subscribing witnesses.
